[57] CLAIM

The ornamental design for a locking hoist hook, as shown
and described.

DESCRIPTION

FIG. 1 is an isometric view of the locking hoist hook of this
invention;

FIG. 2 is a front elevation view thereof;

FIG. 3 is a rear elevation view thereof;

FIG. 4 is a left side elevation view thereof;

FIG. 5 is a right elevation view thereof;

FIG. 6 is a top plan view thereof; and,

FIG. 7 is a bottom plan view thereof.

The broken line showing of a round boss is for illustrative
purposes only and forms no part of the claimed design.
